UNITED STATES PATENT OFFICE

154,974

DESIGN FOR A PORTABLE ENGINE POWER UNIT HOUSING

Peter Altman, Detroit, Mich., assignor to Continental Motors Corporation, Detroit, Mich., a corporation of Virginia

Application December 31, 1947, Serial No. 143,477

Term of patent 14 years

(Cl. D55—1)

To all whom it may concern:

Be it known that I, Peter Altman, a citizen of the United States of America, residing at Detroit, in the county of Wayne and State of Michigan, have invented a new, original, and ornamental Design for a Portable Engine Power Unit Housing, of which the following is a specification, reference being had to the accompanying drawing, forming part thereof, in which

Fig. 1 is a perspective view of a portable engine power unit housing.

Fig. 2 is a plan view thereof.

Fig. 3 is a side elevational view showing the side opposite to that shown in Fig. 1, and

Fig. 4 is an end elevational view showing the end opposite to that illustrated in Fig. 1.

I claim:

The ornamental design for a portable engine power unit housing, as shown.

PETER ALTMAN.
